UNITED STATES PATENT OFFICE

111,958

DESIGN FOR A SCHOOL DESK

Carrie Love Jones Davis, Anniston, Ala.

Application September 15, 1938, Serial No. 79,916

Term of patent 14 years

To all whom it may concern:

Be it known that I, Carrie Love Jones Davis, a citizen of the United States, residing at Anniston, in the county of Calhoun and State of Alabama, have invented a new, original, and ornamental Design for School Desks, of which the following is a specification, reference being had to the accompanying drawing, forming a part thereof.

The figure is a perspective view of a school desk, showing my new design.

I claim:—

The ornamental design for a school desk, substantially as shown.

CARRIE LOVE JONES DAVIS.
